Des. 234,713

Patented Apr. 1, 1975

234,713

PORTABLE FLUORESCENT LIGHT

Milton E. Wilke, Freeport, Ill., and Donald Wayne Doman, Janesville, Wis., assignors to Gould Inc., Chicago, Ill.

Filed July 26, 1974, Ser. No. 492,349

Term of patent 14 years

Int. Cl. D26—02

U.S. Cl. D48—24 R

FIG. 1.

FIG. 2.

FIG. 3.

FIG. 4.

FIG. 5.

FIG. 6.

FIG. 7.

FIG. 1 is a front perspective view of a portable fluorescent light showing our new design;
FIG. 2 is a top plan view thereof;
FIG. 3 is a side elevational view thereof;
FIG. 4 is a front elevational view thereof;
FIG. 5 is a bottom plan view thereof;
FIG. 6 is a rear perspective view, and
FIG. 7 is a rear elevational view thereof.

We claim:

The ornamental design for a portable fluorescent light,
as shown.
